UNITED STATES PATENT AND TRADEMARK OFFICE
CERTIFICATE OF CORRECTION

PATENT NO. : Des. 603,044 S

Page 1 of 1

APPLICATION NO. : 29/329418

DATED : October 27, 2009

INVENTOR(S) : William M. Appling, Theodore J. Beyer and Carol L. Lancette

It is certified that error appears in the above-identified patent and that said Letters Patent is hereby corrected as shown below:

On the Title Pg,

Item (75), please change the inventor's name from "Carol L Lancette" to "Carol L. Lancette"

Item (73), please change "Queensburg" to "Queensbury"

Signed and Sealed this

Twelfth Day of October, 2010

David J. Kappos
Director of the United States Patent and Trademark Office
